UNITED STATES PATENT OFFICE.

JOHN LINDSAY, OF PHILADELPHIA, PENNSYLVANIA, ASSIGNOR TO LINDSAY, HYDE & COMPANY, A FIRM COMPOSED OF JOHN LINDSAY AND JAMES LINDSAY, OF PHILADELPHIA, PENNSYLVANIA.

BUILDER MOTION FOR WINDING MACHINES.

Application filed March 12, 1923. Serial No. 624,464.

To all whom it may concern:

Be it known that I, JOHN LINDSAY, a citizen of the United States, residing in Philadelphia, Pennsylvania, have invented a 5 Builder Motion for Winding Machines, of which the following is a specification.

This invention relates to yarn winding machines, and more particularly to builder motions for such machines, the object of the 10 invention being to provide a builder motion which ceases to operate automatically upon the breaking of the yarn, the invention further residing in the provision of the novel and improving features hereinafter fully set 15 forth.

In the attached drawings:

Figure 1, is a transverse fragmentary section of a portion of a winding machine;

Fig. 2, is a plan view of that portion of 20 the winding machine shown in Fig. 1;

Fig. 3, is a vertical section on the line 3—3, Fig. 2;

Fig. 4, is a section on the line 4—4, Fig. 3, and

Fig. 5, is a section on the line 5—5, Fig. 2.

With reference to the drawings, 1 designates one end of the main frame of a winding machine which supports a table 2, upon each end of which is mounted a standard 3. 30 Extending between these standards 3 is, in the present instance, a pair of tubular rods 4, 4, which support bracket arms 5, which carry the reels 6 from which the yarn is fed to the spools. The spools 7 are each carried 35 by a vertical shaft 8 mounted in suitable bearings in the main frame and having thereon a grooved pulley 9 which is connected by means of a belt 10 with a pulley wheel 11 on the main drive shaft 12, the latter being connected with a suitable source 40 of power (not shown). The shaft 12 also carries a pinion 13 which meshes with a gear wheel 14 on a shaft 15 mounted in the frame, this shaft also carrying a pinion 16 which 45 meshes with a gear 17 on a cam shaft 18. The shaft 18 carries at each end of the frame of the machine a cam 19 which in each instance is engaged by a cam roller 20 on a frame 21 which is vertically reciprocable in 50 the main frame of the machine. The frame 21 is, in the present instance, counterbalanced at each end by a weight 22 connected

with the frame by a chain 23 which passes over a suitable roller 24 on a short shaft 25 secured in the main frame. 55

The frame 21 carries at each end a vertical rod 26 which is slidable in guides 27, 27, on the main frame, the rods 26 supporting at their upper ends a cross bar 28, upon which are mounted the builder motions for the 60 various spools.

The separate builder motions comprise a bracket 29 which is secured to the cross bar 28, and which has therein a bearing 30 for a vertical, threaded shaft 31, a collar 32 secured to the shaft 31 maintaining the shaft in the bearing 30. A second collar 33 is secured to the bottom of the shaft, and interposed between this collar 33 and the bearing 30 is a horizontal arm 34 which is loosely 70 mounted on the vertical shaft and which carries a pawl 35 maintained by means of a spring 36 in contact with the teeth of a ratchet wheel 37, which is fixed to the said shaft 31 and which lies between the arm 34 75 and the bearing 30.

A coiled spring 38 is secured to the arm 34 and to a pin 39 on the bracket 29, said spring tending to maintain the arm 34 in a predetermined position and returning it to 80 this position when the arm is oscillated on the shaft in a manner to be described hereinafter. A spring detent 40 upon the bracket 29 bears against the ratchet 37 and acts as a damper preventing return motion 85 of the ratchet and any motion beyond that given by the pawl 35.

Adapted to travel on the threaded portion of the vertical shaft 31 is a carriage consisting of a ratchet wheel 41 having a downwardly extending hub 42, to which is secured in such manner as to permit free rotation of the hub therein an arm 43, said arm having a rearward extension 44 through which extends a vertical rod 45 which is fixed in 90 an arm 46 of the bracket 29, this rod 45 constituting a guide for the carriage and preventing rotational movement around the shaft 31 of the arm 43. At the forward end of the arm 43 is a receptacle 47 which carries 95 at each end a porcelain guide element 48, 48, and felt pads 49, 49, the purpose of which will be described hereinafter.

The receptacle end of the arm 43 also car-

ries at the top and pivotally secured to a lug 50 thereon a detent 51 which is adapted to engage the teeth of the ratchet 41 and which carries a wire rod 52 which extends in a substantially horizontal position over the center portion of the receptacle 47. A suitable recess 53 is provided in the outer wall of the receptacle 47 to permit downward movement of the arm 55 sufficient to 10 carry the detent 51 clear of the ratchet 41.

Pivotally secured to the top of the ratchet 41 by means in the present instance of a screw 54 is an arm 55 which is threaded at its center portion to correspond with the 15 threaded portion of the shaft 31, and the arm 55 is retained in an advanced position with the threads thereof in engagement with the threads of the shaft 31 by means of a spring 56 which is confined between the back 20 of the arm 55 and a lug 57 on the said ratchet wheel. A pin 58 on the ratchet wheel limits the forward movement of the arm 55 towards the shaft 31.

Secured to the rear side of the receptacle 25 portion 47 of the arm 43, one at each end thereof, is a porcelain guide 59 and 60 respectively which extend upwardly and over the opposite ends of the receptacle.

The operation of the device is as follows: 30 The yarn is wound from the reel 6 onto the spool 7 in the usual manner, the latter being rotated from the main shaft 12 through the belt 10 and the pulleys 11 and 9. The yarn in passing from the reel to the spools 35 is led downwardly and under the guide 60, across the top of the receptacle, and under the guide 59, the guide 60 being hooked at the ends to prevent lateral displacement therefrom of the yarn. Between the guides 40 59 and 60 the yarn passes under the arm 52 of the detent 51, the normal tautness of the yarn being sufficient to maintain the detent in engagement with the ratchet wheel 41. The felt pads 49, 49, in the receptacle 47 may 45 be oiled for the purpose of oiling the yarn as it passes thereover.

During the normal operation of the machine, the frame 21 is reciprocated vertically in the main frame of the machine by the 50 cams 19, such reciprocation being transmitted to the builder motion through the rods 26. At each downward movement of the builder motion, the arm 34 is brought into engagement with a cam 61 adjustably mounted on the table 2, this cam forcing the arm in the direction of the arrow, Fig. 4, against the tension of the spring 38, and through the 55 pawl 35 turning the ratchet 37 through a predetermined angle. Movement of the ratchet 37 carries with it the shaft 31, and through the threaded arm 55 effects a movement of the carriage 41—43 upwardly on the shaft. In this manner, while the entire builder motion is reciprocated opposite the 60 spool 7, the rider is gradually fed upwardly 65

on the shaft 31, with the result that the yarn is built up evenly upon the spool 7 after the well known manner.

In the event of the yarn breaking, the arm 52 of the detent 51, which normally is supported by the yarn, will drop downwardly and retract the detent 51 from the ratchet 41, thereby permitting rotation of the ratchet 41 with respect to the arm 43. As a result of this free rotation of the ratchet 41, the 70 upward feeding of the carriage on the shaft will be interrupted, the ratchet 41 merely turning with the shaft 31 as the latter is actuated by the cam 61. By reason of this interruption of the building action upon the 75 breaking of the yarn, the operator is permitted to mend the break and re-start the winding operation at the exact point that it was left off, the evenness of the winding on the spools thus being preserved. 80

I claim:

1. In a builder motion for winding machines, the combination with a reciprocating structure, of a threaded shaft rotatably mounted in said structure, means for intermittently rotating said shaft through a predetermined angle, a rider slidably mounted on said structure, an element carried by said rider and movable therein, means for retaining the said element immovable in the rider, 90 means for maintaining threaded engagement between the element and the shaft, and means operative when the yarn parts for releasing the element in the rider. 95

2. In a builder motion for winding machines, the combination with a reciprocating structure, of a shaft mounted for rotation in said structure, means for rotating the shaft through a predetermined angle at each reciprocation of the structure, a rider movably mounted on the structure, an element carried by said rider and movable therein and having threaded engagement with the shaft, and yarn-retained means releasable by the parting of the yarn for locking the element 100 in the rider. 105

3. In a builder motion for winding machines, the combination with a reciprocating structure, of a threaded shaft mounted for rotation in said structure, a guide rod on said structure, a rider on said rod, a nut rotatably secured in the rider and having threaded engagement with the shaft, and a movable, yarn-supported element adapted to retain the nut immovable with respect to the 115 rider and to release the nut when the yarn is parted. 120

4. In a builder motion for winding machines, the combination with a reciprocating structure, of a threaded shaft rotatably mounted in said structure, means for intermittently rotating said shaft through a predetermined angle, a rider movably mounted on the structure, an element carried by the rider and movable therein, a threaded mem- 125 130

ber carried by said element and adapted to engage the threaded portion of the shaft, means for breaking the threaded engagement between said member and the shaft, and yarn-retained means releasable by the parting of the yarn for locking the said element in the rider.

5. In a builder motion for winding machines, the combination with a reciprocating structure, of a threaded shaft mounted for rotation in said structure, means for intermittently rotating said shaft through a predetermined angle, a rider movably mounted on the structure, an element rotatably mounted in the rider and embracing the shaft, means for releasably retaining said element immovable in the rider, a threaded member movably mounted on said element and adapted to engage the threaded portion 20 of the shaft, and a spring tending to retain said element in engagement with said shaft.

6. In a builder motion for winding machines, the combination with a reciprocating structure, of a shaft mounted for rotation in said structure, a ratchet wheel secured to said shaft, an arm loosely mounted on said shaft and having a pawl adapted to engage the teeth of the ratchet, means for intermittently reciprocating said arm to advance 25 the ratchet wheel through a predetermined angle, a rider movably mounted in said structure, an element carried by the rider and having threaded engagement with the shaft, and releasable means for retaining the 30 said element immovable in the rider.

7. In a builder motion for winding machines, the combination with a reciprocating structure, of a threaded shaft mounted for rotation in said structure, a ratchet wheel fixed to said shaft, an arm loosely mounted 40 on said shaft, a pawl carried by said arm and adapted to engage the teeth of the ratchet, a cam located in the path of said arm and adapted at each reciprocation of the structure to shift the arm through a predetermined angle, a rider movably mounted on the structure, an element carried by the rider and movable therein and having threaded engagement with the shaft, and 45 yarn-controlled means for releasably retaining the element immovable in the rider.

8. In a builder motion for winding machines, the combination with a reciprocating structure, of a threaded shaft mounted for rotation in said structure, means for intermittently rotating the shaft through a predetermined angle, a guide rod fixed in the structure and extending parallel to the shaft, a rider having a pair of spaced openings for the reception of the guide rod and 50 the shaft, an element rotatably mounted in the latter opening and having a passage concentric with the opening in the rider which it occupies for the reception of the shaft, releasable means carried by said rider for maintaining threaded engagement with the shaft, and yarn-controlled means for 55 releasably retaining the element immovable in the rider.

JOHN LINDSAY.
